UNITED STATES PATENT OFFICE.

WILLIAM R. PHILLIPS, OF TRENTON, NEW JERSEY.

APPLE-PARING MACHINE.

954,340.

Specification of Letters Patent.

Patented Apr. 5, 1910.

Application filed April 25, 1907. Serial No. 370,283.

To all whom it may concern:

Be it known that I, WILLIAM R. PHILLIPS, a citizen of the United States, residing at Trenton, in the county of Mercer and State 5 of New Jersey, have invented certain new and useful Improvements in Apple-Paring Machines, of which the following is a specification.

My invention relates to improvements in 10 machines for slicing and paring fruit of a certain kind, as apples, pears, peaches, and the like, as well as for coring the same, also for peeling and slicing potatoes.

Said invention has for its object to secure 15 the aforesaid results in a simple and effective manner and to promote simplicity, as well as to cheapen manufacture.

It therefore consists of sundry features or instrumentalities substantially as hereinafter 20 fully disclosed and specifically pointed out by the claims.

In the accompanying drawing illustrating the preferred embodiment of my invention—Figure 1 is a side elevation thereof. Fig. 2 25 is an opposite side elevation of the same. Fig. 3 is a plan view thereof, and Fig. 4 is a sectional elevation produced transversely through the machine. Fig. 5 is an end elevation thereof. Fig. 6 is a detached perspective view, taken from the underside of the guide-bar. Fig. 7 is a detached perspective view of the knife carriage. Fig. 8 is a view showing the machine equipped for the treatment of vegetables as potatoes for slicing 35 the same.

In carrying out my invention, I mount the operative parts thereof upon a suitable frame or casting 1 adapted for retention in rigid position at any convenient point as 40 will be readily understood.

A screw or worm shaft 2 suitably journaled in position and intergeared as at 3 with a crank or handle is equipped with an interiorly toothed gear-wheel 4. Said shaft 45 has mounted so as to travel thereon a carriage 5, the latter having alining openings with a sleeve 6 between said openings for the passage through the same of said shaft but not having screw-threaded engagement therewith. Said carriage has a downward extension 7 having in its lower end a notch receiving an edgewise-arranged rib or rail 8 integral with the frame or casting 1 for the effective guidance and stability of said carriage. Also said carriage is equipped with, 50 and carries a paring knife 9 preferably of

the construction disclosed, comprising a flat surfaced block or head 10 rounded at its forward edge, and a curved edgewise-arranged blade 11 having its ends suitably secured to 60 said head by a screw-bolt and conformable to the rounded forward edge thereof but outstanding from the latter sufficiently for effecting the paring of the fruit as it is juxtaposed thereto in the usual way. A stem 65 or rod 12, to which said block or head is held by a set-screw 13, has a right-angled lower end-portion pivoted in an aperture in the corresponding portion of the extension 7 of the carriage 5; and said stem or rod 12 is 70 controlled by preferably two helical or coiled springs 14 connected thereto and to said carriage, holding said stem forcibly against the latter and the knife in effective position. Said stem or rod is also equipped 75 with a cam projection 15 extending in under the top-plate of the carriage 5, the function of which will be made apparent later.

A handle-equipped dog 16 suitably pivoted to and carried by the carriage 5, has 80 its effective inner portion adapted for engagement with the screw shaft 2, also with a guide or holding bar later described, said dog being, however, normally held automatically out of such engagement with the 85 parts noted by the action of a preferably coiled spring 17. Said spring is adapted to exert downward pressure upon the outer arm of said dog for that purpose, it receiving at its upper end a stud or pendant 18 of 90 said dog and receiving at its lower end an upstanding terminal of a plate or bracket 19 held preferably by a bolt or screw to the underside of the carriage 5. The dog 16 has an integral lateral extension or arm 20 95 for engagement with the cam-projection 15 on the rod 12 for affecting the action of the paring knife as will be later seen. The carriage has connected thereto in any suitable way one end of a preferably coiled or helical 100 spring 21, connected at its opposite end preferably to a thumb-screw 22 threaded into the frame 1 and which may serve for compensating tension of the spring as required, said spring being designed to provide for automatically returning the carriage to its initial position after performing its forward movement as will presently appear. A stop 23 preferably in the form of an edgewise-disposed plate removably 105 held upon the rear end upright of the frame 1 and having a right-angled or bent portion

equipped with a cushion or buffer 24, is adapted to reduce the concussion which would otherwise occur and arrest the return movement of the carriage as the spring 21 5 delivers its stress or pressure upon the latter.

A preferably tubular rod or mandrel 25 capable of reciprocating is held in an upper end tubular bracket 26 of the rear end upright of the frame 1; and into the forward 10 end of said rod or mandrel may be screwed or held either a tubular corer 27, or a pin 28, as it may be desired to core fruit, as an apple or the like, or support a vegetable as a potato for treatment, as in slicing the 15 same. A brace or rod 29 has one end hooked into an aperture in the top-plate of the knife-carriage 5 and its upper end provided with an upstanding eye-ended terminal adapted to allow the insertion through it 20 of the extension of the corer 27, or of the pin 28, whichever may be desired for use, in connecting either of these latter to the mandrel 25, said rod or brace thus serving to effect connection between said mandrel, 25 carrying said corer or pin, and the knife-carriage.

A "push-off" 30, consisting of a bent, edgewise-arranged plate, is removably held at its rear end laterally upon the bracket 30 26 of the rear end upright of the frame 1, with its bent or lateral forward end portion rounded out and adapted to provide for the passage therethrough of the corer 27 as the latter is connected to the mandrel 25 35 as will be readily understood.

A preferably tri-bladed or winged holder 31 effective for stabbing and holding the fruit for treatment, is arranged at the opposite or forward end of the machine, the 40 same terminating one end of a shaft or spindle 32 suitably journaled in that end upright, which spindle or shaft is driven by a pinion 33 fixed thereon and meshing with the internal toothed wheel 4 as the latter is 45 actuated as is obvious.

A guide-bar 34 is suitably fixed to, and offset laterally from the frame 1, oppositely to, and so as to allow of the engagement therewith of the extreme inner or lower end 50 of the dog 16, said bar having in its underside, near the edge next to the dog and contiguous to its forward end, an upward curved cam groove 35; opposed to which is a guard-plate 36 fixed to the underside of said guide-bar. Also just forward of said cam-groove 55 is a notch 37 indenting laterally said guide-bar. Again, indenting said guide-bar laterally, along the same edge, at a point which will allow the escape of the point or extreme 60 inner end of the dog when the knife-carriage has reached the end of its return movement, is a recess or slot 38, which, when desired, may be filled-in or closed by a set-screw held 65 slide or closure 39 as when it may be desired to shorten or lengthen the travel or

return movement of the knife-carriage; in that event an additional recess or slot as at 40 being provided in said edge of said guide-bar for the escape of the point of said dog.

It will be noted that, when the knife-carriage 5 has moved, in its forward travel, so that the point of said dog will ride up into the cam-groove 35 and during such movement, the knife will move inward following the action of the arm 20, and thereby treating the butt of the apple around the stem-portion, said point of dog then passing out of said groove and accordingly downward and forward bringing the knife back to initial position. The point of said dog will finally escape upward out through the notch 37 to the upper side of the guide-bar, when the action of the spring controlling the dog will have disengaged it (the dog) from the screw-shaft, thus allowing the sending of the knife-carriage back to its starting point for a like operation. When the knife-carriage has moved to the extreme limit of its forward movement the 90 corer, it will be noted, will have penetrated clear through the fruit thus decoring it, and that, when the carriage makes its return transit, the fruit thus pared and decored will be brought into forcible contact with the "push-off", since the latter will stand just sufficiently in rear of the forward end of the corer to be thus acted upon and provide for automatically ejecting or pushing the fruit off said corer.

When it may be desired to treat or slice and peel potatoes, the various parts used in treating fruit as above noted are dismantled and the machine organized as disclosed by Fig. 8, the knife 41 with the lateral point 42 substituting the previously used paring knife and the slide 39 screwed into such position as to fill-in or close the slot or recess 38, as indicated.

It will be appreciated that this machine 110 is simple in construction, readily and advantageously operated and cheaply manufactured.

I claim—

1. A device as described, comprising a 115 knife-equipped carriage, a spring controlled dog carried by said carriage, a guide-bar in engagement with one end of said dog, a screw-shaft engaging said dog, said dog having its handle-member provided with an arm engaging a cam-projection upon the knife stem, a spring for controlling the movement of the knife stem, said guide-bar being adapted to coöperate with said dog 120 for effecting the aforesaid engagement between said arm and said cam-projection to cause said knife to perform a curving movement just before the knife-carriage reaches the limit of its forward movement.

2. In an apple paring machine, the com- 130

- bination with a frame, of a screw shaft mounted thereon, a carriage mounted on the shaft, a spring controlled dog on the carriage, a guide bar adapted to engage the dog for throwing it into engagement with the screw shaft, a knife mounted on the carriage, and means for rotating the screw shaft whereby the carriage is moved and the knife caused to engage the fruit.
- 5 3. A device as described, comprising a knife-carriage having a spring-controlled dog provided with an arm effecting engagement with a cam-projection upon the knife-stem, a spring for controlling the movement of the knife stem, a screw-shaft for transmitting movement through said dog to said carriage, a tripping guide-bar for said dog, and a spring for controlling the return movement of said carriage, and means for 15 actuating said shaft.
- 10 4. A device as described, comprising a knife-carriage equipped with a spring-controlled dog, a spring for controlling the return movement of said carriage, a screw-shaft, means for actuating said shaft, a 25 sliding mandrel, a "push-off" fixed with relation to said mandrel, a corer carried by said mandrel, means effecting fixed connection between said carriage and said mandrel, a guide-bar being equipped with a cam-groove for engagement with the point of said dog and having a closure-controlled slot or recess for the escape of the point of said dog therethrough, said dog being provided with means for controlling the action of the knife carried by said carriage.
- 20 In testimony whereof I affix my signature, in presence of two witnesses.
